UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

HEADER.

1,241,693.

Specification of Letters Patent.

Patented Oct. 2, 1917.

Application filed August 23, 1915. Serial No. 46,939.

To all whom it may concern:

Be it known that I, RICHARD LESTER WILCOX, a citizen of the United States, residing at Waterbury, in the county of New Haven and State of Connecticut, have invented certain new and useful Improvements in Headers, of which the following is a specification, reference being had therein to the accompanying drawings.

10 My invention relates to new and useful improvements in headers of the open die type, and has for its object, among other things, to construct such a header so that the dies in opening and closing will move in 15 the direction of their length instead of at right angles thereto, as has heretofore been the practice, and as a result thereof, produce a device that will be equally as efficient as the old form of headers and much less complicated.

To these, and other ends, my invention consists in the header, having certain details of construction and combinations of parts as will be hereinafter described and 25 more particularly pointed out in the claims.

Referring to the drawings, in which like numerals of reference designate like parts in the several figures;

Figure 1 is a fragmentary plan view of 30 one end of a header having my improvements attached thereto;

Fig. 2 is a sectional elevation thereof taken substantially upon line A—B;

Fig. 3 is an enlarged sectional view of the 35 knock-out and adjacent mechanism;

Fig. 4 is a face view of the die sections in their closed relation;

Fig. 5 is an enlarged side elevation of the 40 punch block, the punches therein being shown partly in section; and

Fig. 6 is a perspective view of one of the wedge keys.

In open die, bolt heading machines, heretofore made, the dies are opened slightly by 45 moving the sections away from each other in a lateral direction, and after the wire has been fed therebetween are closed again to substantially their original position, then moved as a unit at right angles to the direction of the wire feed until the axis of the wire is substantially coincident with the axis of the punch in its upsetting position.

Much complicated, powerful mechanism is required to move these dies in substantially

the manner as above indicated and hold 55 them together during the upsetting operations.

There are objections to the old form of open die header, other than those indicated, that are obviated in my present invention. 60

My improved header is constructed so that the dies do not move in a lateral path, but in a direction substantially parallel with the movement of the punches and the wire feed, and by reason thereof all of the mechanism 65 heretofore used for closing the dies and keeping them in their closed position during the upsetting operation is discarded, thereby very materially reducing the number of parts required, the original cost of 70 the machine, as well as the maintenance thereof, and making possible the use of a smaller sized header for the same size of work. In fact, substantially the same results are obtained with my improved open 75 die mechanism in a solid die header of substantially the same size, a result not heretofore possible.

In the drawings I have only illustrated the die end of a header, the other mechanisms not being material to my present invention, and may be of the usual form or type.

The numeral 1 designates the body of the header, 2 the gate having a reciprocatory 85 movement therein, 3 the punch block which is secured to the slide 4 and has a reciprocatory movement in the gate 2 during the movement of said gate, and 5 and 6 the punches.

I have illustrated only two punches, but more or less may be used, as may be necessary to produce the desired result.

The die block is designated by the numeral 7 and is held within a recess 8 in the 95 body 1 by the clamp block 9 having an angular face 10 thereon that contacts with the angular face 11 upon said die block. A bolt 12, having a nut 13 thereon and passing through the clamp block 9 and body 1, rigidly secures both the die and clamp blocks 100 in their locked positions.

To assist the clamp block 9 in holding the die block in its proper relative position, and to prevent the same from slipping by 105 gravity, shock, etc., I have provided supporting means therefor, which consists of the plate 46 secured to the bed 1, and

through which is threaded a screw 47, the end of which impinges against the head of one of the screws 26 and prevents the die block from shifting downwardly, a check 5 nut 48 upon the screw 47 locking the same in any of its adjusted positions.

Movably mounted within a tapered hole 14 in the die block 7 are the die sections 15, which, as shown herein, are semi-circular in 10 cross section and tapered rearwardly from their front end, this taper being the same as that of the tapered hole 14. In the inner face of each of these die sections is a semi-circular recess 16 terminating at its outer 15 end in an enlarged angular section 17, the cross section of which is substantially the same as that of the head of the bolt. The diameter of the recess 16 is substantially the same as that of the wire rod and the shank 20 of the bolt and it terminates at its rear end in the shoulder 18, from which and to the rear end of the section is an opening 19, preferably, although not necessarily, of smaller diameter than the recess 16.

25 Slidably mounted within the opening 19 is a knock-out pin 20, having a head 21 thereon of substantially the same diameter as the recess 16 and supported at its other end in a sleeve 22, within the bore of the 30 knock-out sleeve 23 fixed within the body 1, the inner end of which abuts the rear end of the die sections.

The die sections are held in proper alignment with each other by the dowel pin 24, 35 which is preferably fixed in one section and slidable within the other. This dowel pin may be located in any convenient position in the sections. Other means, than the dowel pin, may be substituted to insure the 40 alignment of these die sections, and, as is desirable in some cases, the cross section of the die sections may be angular instead of circular, in which case no such alining device is required.

45 The die sections are separated during their movement in one direction by one or more keys 25 that are secured within the die block 7 by the screws 26 and have wedge faces 27 thereon that lie within the grooves 28 in 50 the opposite sides of the die sections 15.

The walls 29 of the grooves 28 are substantially parallel with the wedge faces 27, so that as the die sections 15 are moved toward the gate 2, they are spread apart by 55 reason of the engagement of said walls and wedge faces. This movement insures the separation of the die sections and the creation of an open space between the faces thereof, while said sections are moving toward the gate.

Upon one side of the body 1, within which the slides 30 and 41 have a reciprocatory movement, through the action of one or more cams, or similar mechanism, as is common 60 in headers and not material to this inven-

tion, the screws 42 and 43, pivotally connected with the slides by the pintles 44 and 45, form one means of connecting the slides with such mechanism.

The companion knock-out levers 32 are 70 pivotally connected with the lug 33 upon the body 1 by the pintle 34 and are moved in one direction by the slide 30, through the adjusting screw 35, having a head 36 thereon that engages both of the levers 32 and 75 a lock nut 37, to prevent accidental movement thereof.

The knock-out pin 20 is moved toward the gate 2 through the rod 38 that is slidably mounted within the knock-out sleeve 23, and 80 having contact with the knock-out lever 39 that is pivotally mounted upon the pintle 34 and engages the adjustable pin 40 that is threaded in the slide 41.

As the slides 30 and 41 reciprocate, the 85 levers 32 and 39 are actuated and the knock-out sleeve 23 moves toward the gate 2 and moves the die sections parallel therewith and by reason of the keys 25 the die sections are separated slightly, the extent of 90 the separation being determined by the extent of movement of said sleeve.

Movement of the lever 39 actuates the knock-out pin 20 through the rod 38 and strips from the die sections anything that 95 is within the recesses 16.

The wire is fed in the usual manner through a cut-off die 49 mounted within the die block 7, in line with the feed rolls 50, one of which is shown in Fig. 1 to illustrate 100 its relative position.

The stop mechanism for limiting the feed of the wire, comprises a rod 51 that is adjustable toward and away from the face of the die by a screw 52 and adjacent mechanism, in a manner well known in the art, and a stop arm 53 fixed to the inner end of the rod 51 with a hardened button 54 in the outer end thereof, against which the wire abuts after passing through the cut-off die 110 49. After the wire has engaged the stop mechanism, it is cut off the required length and the cut off portion is transferred to a position wherein its axis is substantially coincident with the center of the die sections. Any one of many means may be utilized to accomplish this purpose, and I have therefore only illustrated one of them, which in fact constitutes no part of my present invention. This mechanism consists of a 115 slide 55 that has a reciprocatory movement toward and away from the die sections by means not herein shown, having secured to the inner end thereof a cut-off knife 56 by the screw 57, the carrier bar 58 that is 120 secured to a plate 59 connected with the slide 55 by the bolt 60 and slidably mounted within the lug 61 upon the body 1. Pivotally mounted to the inner end of the carrier bar 58, upon the finger bolt 62, is the spring 125

5 arm 63, between the outer end of which and the carrier bar 58 is a coil spring 64 mounted upon the rod 65. The action of this spring is such as to normally force the outer end of the arm 63 away from the carrier bar 58 rotating the bolt 62 and the spring finger 66 which projects downwardly with the lower end thereof opposite the edge of the knife 56, substantially as shown in Fig. 2.

16 When the wire, designated in the drawings by the numeral 67, is advanced through the cut-off die 49, it passes between the cutter knife 56 and spring finger 66, the spring 64 exerting a tension upon said spring finger and holds the blank, when cut off, against the edge of the knife 56 with sufficient friction to support it, while the slide 55 is moved toward the die sections and presents the blank with its axis substantially coincident 20 with the center of the die sections.

In operation, the wire is fed in the usual manner, as above indicated, and a portion cut therefrom, then transferred to a position in line with the die sections, which are now moved through the knock-out mechanism so that the inner faces thereof are separated a sufficient distance to permit the blank to pass therebetween. During this time the punch 5 moves upwardly and contacts with the outer end of the blank and pushes it from between the cut-off knife and finger 66 between the die sections until the inner end abuts against the head 21 of the knock-out pin 20, which is forced rearwardly, 35 and with it, the die sections 15 by reason of the engagement of the head 21 with the shoulder 18. The die sections are thus closed against each other by reason of the engagement of their exterior tapered portion with the tapered hole 14 in said die block. After the blank has passed into the die sections sufficiently to support it, the bar 55 is withdrawn and the finger 66 snaps over the blank as the pin 62 rocks upon its 45 pivot mounting against the tension of the spring 64. After passing over the blank, the spring 64 returns the finger 66 to substantially the same relative position with the bar 55 as is shown in Fig. 2, and is thus 50 ready for the next succeeding blank. In the closed position of the dies the blank is held tightly therebetween within the recesses 16, and the continued movement of the gate causes the die 5 to partially upset the end 55 thereof. The die sections, and the partially completed blank, remain in this position while the punch 5 is withdrawn and the punch 6 moved so that its axis is in alignment with and engages the partially completed blank, making a further upsetting thereof and completing the bolt. This latter punch is then withdrawn and moved within the gate 2 so as to again present the punch 5 into alignment position with the 60 axis of the die sections. While this latter

movement of the punches is under way the knock-out sleeve 23 moves the die sections within the die block toward the gate 2 causing the same to open and free the completed blank therebetween and the knock-out pin 70 20 ejects it therefrom, and the same, as a completed article, drops into a receptacle conveniently arranged to receive it. Succeeding blanks are presented to the die sections and the operations performed as before. 75

New knock-out pins 20 with heads 21 of varying lengths are substituted so as to permit the use of the same die sections for blanks of various lengths, the end of the 80 blank abutting against the outer end of this head.

In the drawings I have illustrated the die sections and punches as designed for the construction of a carriage bolt, but this is 85 only one of the many forms of bolts that may be manufactured in my mechanism. I believe it possible to manufacture any form of bolt in my header, including those having lugs or protuberances thereon, by merely changing the shape of the recesses 16, the metal in the blank flowing into and filling said recesses by the upsetting action of the punches. 90

95 Many minor details of my invention can be modified from those shown in the drawings, and I would therefore have it understood, that I do not limit myself to the exact construction herein shown and described, but claim all that falls fairly within the 100 spirit and scope of the appended claims.

Having described my invention, what I claim as new and desire to secure by Letters Patent, is:—

1. In an open die header, the combination 105 with a plurality of die sections, each of said sections having a recess in one face thereof; a reciprocating punch; means for mounting said sections, whereby said punch will move said die sections in a path substantially parallel therewith; and positively actuated independent means for moving said die sections in the opposite direction.

110 2. In an open die header, the combination with a plurality of die sections, each of said sections having a recess in one face thereof; a reciprocating punch; means for mounting said sections, whereby said punch will move said die sections in a path substantially parallel therewith; a reciprocating member having contact with said die sections for moving said die sections in a path substantially parallel therewith but in a direction opposite to that imparted by said punch; and positive means for actuating said reciprocating member. 120

125 3. In a header, the combination with a plurality of independent die sections, each having a tapered exterior and a face that contacts with a similar face upon an ad-

- 4
- jacent die section; of means for moving said die sections toward each other and in a path at substantially a right angle thereto, said means comprising a block having a tapered opening therein, a reciprocating member, having contact with said sections at one end, a reciprocating member, having contact with said sections at the opposite end, and positively actuated means for independently moving each of said reciprocating members in one direction.
4. In an open die header, the combination with a plurality of die sections, each of said sections having a recess in one face thereof; a reciprocating punch movable toward and away from said die sections; means for mounting said die sections whereby they will be opened and closed while traveling in a path substantially parallel with said punch and so that the heading pressure of said punch thereon will have a tendency to maintain the dies in their closed relation; and means for ejecting a blank from between said sections.
5. In an open die header, the combination with a plurality of die sections, each of said sections having a recess in one face thereof; a reciprocating punch movable toward and away from said die sections; means for mounting said die sections whereby they will be opened and closed while traveling in a path substantially parallel with said punch and so that the heading pressure of said punch thereon will have a tendency to maintain the dies in their closed relation; means for ejecting a blank from between said sections; and means for imparting an independent movement to said ejecting means.
6. In an open die header, the combination with a plurality of die sections, each of said sections having a recess in one face thereof; a reciprocating punch movable toward and away from said die sections; means for mounting said die sections whereby they will be opened and closed while traveling in a path substantially parallel with said punch and so that the heading pressure of said punch thereon will have a tendency to maintain the dies in their closed relation; means for ejecting a blank from between said sections, said means accommodating blanks of various lengths in the same die section.
7. In an open die header, the combination with a plurality of die sections each of said sections having a recess in one face thereof; a reciprocating punch; means for mounting said die sections whereby they will be opened and closed while traveling in a path substantially parallel with said punch and so that the heading pressure of said punch thereon will have a tendency to maintain the dies in their closed relation; means for accommodating blanks of various lengths in the same die section, comprising a member

held between said die sections and forming a backing for the blank while being operated upon by said punch; and means for imparting a reciprocatory movement to said member for ejecting blanks from said die sections.

8. In an open die header the combination with a plurality of die sections, each of said sections having a recess in one face thereof; a reciprocating punch; means for mounting said die sections whereby they will be opened and closed while traveling in a path substantially parallel with said punch; and means for ejecting a blank from between said sections, said ejecting means having such an engagement with said die sections as to move the same therewith while moving in one direction.

9. In an open die header, the combination with a plurality of die sections, each of said sections having a recess in one face thereof; a reciprocating punch; means for mounting said die sections whereby they will be opened and closed while traveling in a path substantially parallel with said punch and so that the heading pressure of said punch thereon will have a tendency to maintain the dies in their closed relation; means for ejecting a blank from between said sections; and means for imparting an independent movement to said ejecting means by positively actuated mechanism, in one direction, and by the movement of the blank in the opposite direction.

10. In a header, the combination with a plurality of die sections, each having a tapered exterior and a face that contacts with a similar face upon an adjacent die section; of means for moving said die sections toward each other and in a path at substantially a right angle thereto, said means comprising a block having a tapered opening therein; a reciprocating member having contact with said sections; positively actuated means for moving said reciprocating member in one direction; and means for ejecting a blank from between said sections operative between said sections.

11. In a header, the combination with a plurality of die sections, each having a tapered exterior and a face that contacts with a similar face upon an adjacent die section; of means for moving said die sections toward each other and in a path at substantially a right angle thereto, said means comprising a block having a tapered opening therein; a reciprocating member having contact with said sections; positively actuated means for moving said reciprocating member in one direction; means for ejecting a blank from between said sections, having a part thereon within the recesses in the abutting faces of said sections; and means for positively actuating said ejecting means in one direction.

12. In a header, the combination with a

- plurality of die sections, each having a tapered exterior and a face that contacts with a similar face upon an adjacent die section; of means for moving said die sections toward each other and in a path at substantially a right angle thereto, said means comprising a block having a tapered opening therein; a reciprocating member having contact with said sections; positively actuated means for moving said reciprocating member in one direction; means for ejecting a blank from between said sections movably mounted within said reciprocating member; and means for actuating said ejecting means independently of said reciprocating member.
13. In an open die header, the combination with a plurality of die sections, each of said sections having a recess in one face thereof; a reciprocating punch; means for mounting said sections, whereby said punch will engage and move said die sections in a path substantially parallel therewith; independent means for moving said die sections in the opposite direction, comprising a reciprocating member having contact with said die sections; and means for actuating said reciprocating member, said means comprising a slide and a rock member between said slide and reciprocating member having engagement with both said reciprocating member and said slide.
14. In a header, the combination with a plurality of die sections, each having a tapered exterior and a face that contacts with a similar face upon an adjacent die section; of means for moving said die sections toward each other and in a path at substantially a right angle thereto, said means comprising a block having a tapered opening therein; a reciprocating member having contact with said sections; positively actuated means for moving said reciprocating member in one

direction; means for ejecting a blank from between said sections movably mounted within said reciprocating member; and means for actuating said ejecting means independently of said reciprocating member, the means for actuating the said reciprocating member and ejecting means comprising independently actuated slides and rock members engaging said slides and said reciprocating member and ejecting means.

15. In an open die header, the combination with a plurality of die sections, each of said sections having a recess in one face thereof; a reciprocating punch movable toward and away from said die sections; means for mounting said die sections whereby they will be opened and closed while traveling in a path substantially parallel with said punch; means for ejecting a blank from between said sections, said ejecting means being operated between said die sections and having such an engagement therewith as to move the same while traveling in one direction.

16. In an open die header, the combination with a plurality of die sections, each of said sections having a recess in one face thereof; a reciprocating punch movable toward and away from said die sections; means for mounting said die sections, whereby they will be opened and closed while traveling in a path substantially parallel with said punch and so that the heading pressure thereon will have a tendency to maintain the dies in their closed relation; means for ejecting a blank from between said sections and forming a backing for the blank in said die while the same is being operated upon by said punch.

In testimony whereof I have hereunto affixed my signature:

RICHARD LESTER WILCOX.
